UNITED STATES PATENT OFFICE.

RICHARD HAKING PARKINSON, OF LONDON, ENGLAND, ASSIGNOR TO ATTRACTIVE PUBLICITY, LIMITED, OF LONDON, ENGLAND.

WINDING MECHANISM FOR ENDLESS BANDS OR FILMS FOR CINEMATOGRAPHS OR OTHER MACHINES.

Application filed December 9, 1922. Serial No. 605,895.

To all whom it may concern:

Be it known that I, RICHARD HAKING PARKINSON, a subject of the King of Great Britain, residing in London, England, have **5** invented certain new and useful Improvements in Winding Mechanism for Endless Bands or Films for Cinematographs or Other Machines, of which the following is a specification.

10 This invention relates to winding mechanism for endless films for cinematograph or other machines and it relates to mechanism for dealing with a roll of film or other material in which the film is taken from the **15** center of the roll and rewound upon the outer circumference thereof.

The present invention has for its object to provide mechanism which may be run for long periods of time without the convolutions becoming unduly tight, whereby not **20** only is the film apt to become broken but the friction between the convolutions causes the film to become worn.

A further object of the invention is to provide mechanism whereby a length of film **25** may be dealt with which is considerably in excess of the length of film which may be handled by existing mechanisms.

In order to overcome the aforesaid objections according to this invention there is embodied in the mechanism a roller or plurality of rollers each of which engages, and is driven by, the inner convolution of the film and with which roller is associated a **35** disc or plate engaging the edge of the convolutions of the roll of film and which disc or plate is driven at a speed co-incident with the speed at which the film is passed through the machine, other rollers driven by the **40** film co-operate with the aforesaid disc and roller or discs and rollers to support said film. If desired the roller or rollers with which the disc or discs is associated may also be positively driven at a speed co-incident **45** with that of the inner convolution of the roll.

In order that the invention may be the better understood drawings are appended in which:—

50 Fig. 1 is a front elevation showing one embodiment of the present invention,

Fig. 2 is a section on line A A Fig. 1,

Fig. 3 is a section to a larger scale of a film sprocket,

Fig. 4 is a section of one of the rollers **55** showing the disc associated therewith,

Fig. 5 is a side view of the sprocket and cradle rollers.

Fig. 6 is a section on line B B of Fig. 5.

Referring to the accompanying drawings **60** 1 indicates a base plate or support.

The plate 1 is perforated and a screw thread formed in the perforation to engage a thread formed upon a sleeve or bearing 2, in which is mounted a spindle 3, to which is secured a disc 4, the method of attachment preferably being such that the disc may be readily disconnected to which end a pin 4^a is provided which passes through the base of the disc and into the spindle its head projecting as shown whereby it may be readily grasped for removal.

Mounted upon spindle 3 in a manner such that it is revoluble independently thereof, preferably by means of ball bearings, indicated generally by 5, is a roller 6 the said roller engaging the inner convolution of the roll of film *x*, whilst the disc 4 engages the edge of the roll. The spindle 3 is driven in any suitable manner such that the disc **80** rotates at a speed co-incident with the speed at which the film travels through the machine, the roller 6 being driven by the inner convolution of the roll with which it contacts.

There are a number of discs and rollers such as that just described arranged as shown in Fig. 1 and co-operating with these are rollers 7 mounted on spindles 8 carried by plate 1 the respective rollers being so arranged that the film is divided into a number of separate runs which unite at *x*^a being supported at this point by other rollers 9 which rollers engage the inner convolution of the roll and are driven thereby. The **90** rollers 9 are adjustably mounted upon plate 1 by means of nuts *w* which engage screw-threads upon the ends of the spindles which ends pass through inclined openings 1^a in plate 1.

100 10 indicates a sprocket drum engaging the film and over which it passes from the machine to the winding mechanism.

Bearing upon the film and pressing same of drum 10 are cradle rollers 11 mounted upon arms 12 pivotally mounted upon a frame 13 secured to plate 1. A spring 14 ensures the necessary pressure of the rollers

- 11 upon the film. The film passes around the sprocket drum to the upper run of the film being drawn off from the interior of the roll by a second sprocket drum 15 actuated 5 in any suitable manner from the sprocket by which the film is fed through the gate of the machine.
- In order to prevent the film from wrapping round the sprocket drum 15 there is 10 provided a plate 16 of substantially V-shaped outline and which plate is supported by a pin or stud 17 projecting from the face of the plate 1 and arranged as shown in Figs. 1 and 5.
- 15 In order to prevent the lateral displacement of the convolutions of the film rollers are provided indicated by 18, 18^a which rollers are mounted upon spindles 19 mounted respectively in slots or openings 20 indicated by 19^a and formed in plate 1 and upon spindles 19^b supported by columns 20 which columns are at their bases provided with lugs 21 whereby the columns are mounted upon the plate 1.
- 25 Motion is imparted to the various discs 4 from the spindle of the sprocket drum 15 by means of a belt 22 passing over a pulley 22^a on the spindle of the said disc and engaging other pulleys 23 upon the spindles of 30 the other disc.

Motion is transmitted to the sprocket drum 10 being driven by means of a chain 24 passing over a chain wheel 15^a on the spindle of the sprocket drum 15.

35 Claims

1. Winding apparatus for endless bands or films comprising film supporting rollers engaging the inner convolutions of the roll and driven thereby other rollers engaging 40 the inner convolution of the roll and driven thereby, discs associated with said second rollers and engaging the edge of the film and driven at a speed co-incident with the speed at which the film passes through the machine, a sprocket drum over which the film passes to the roll of film, a second sprocket drum over which the film passes to the machine, said sprocket drums being driven at a speed co-incident with the speed at which the film passes through the machine.
2. Winding apparatus for endless bands or films comprising film supporting rollers engaging the inner convolution of the roll and driven thereby, other rollers engaging 55 the inner convolution of the roll and driven thereby, discs associated with said second rollers and engaging the edge of the film and driven at a speed co-incident with the speed at which the film passes through the machine, a sprocket drum over which the film passes to the roll of film, a second sprocket drum over which the film passes to the machine, said sprocket drums being driven at a speed co-incident with the speed at which the film passes through the machine.
- 60

machine the respective rollers and discs being so arranged that the main body of the roll is formed into a number of separate runs.

3. Winding apparatus for endless bands 70 or films comprising film supporting rollers engaging the inner convolution of the roll and driven thereby, other rollers engaging the inner convolution of the roll and driven thereby, discs associated with said second rollers and engaging the edge of the film and driven at a speed co-incident with the speed at which the film passes through the machine, a sprocket drum over which the film passes to the roll of film, a second sprocket drum over which the film passes to the machine, said sprocket drums being driven at a speed co-incident with the speed at which the film passes through the machine the respective rollers and discs being 75 so arranged that the main body of the roll is formed into a number of separate runs, and means for preventing the lateral displacement of the film upon the various rollers.

4. Winding mechanism for endless bands or films comprising film supporting rollers engaging the inner convolution of the roll and driven thereby, other rollers engaging the inner convolution of the roll and driven 80 thereby, discs associated with said second rollers and engaging the edge of the film and driven at a speed co-incident with the speed at which the film passes through the machine, a sprocket drum over which the film passes to the roll of film, a second sprocket drum over which the film passes to the machine, said sprocket drums being driven at a speed co-incident with the speed at which the film passes through the machine the respective rollers and discs being 85 so arranged that the main body of the roll is formed into a number of separate runs, and means for preventing the lateral displacement of the film upon the various rollers.

5. Winding mechanism for endless bands or films comprising film supporting rollers 90 engaging the inner convolution of the roll and driven thereby, other rollers engaging the inner convolution of the roll and driven thereby, discs associated with said second rollers and engaging the edge of the film 95 and driven at a speed co-incident with the speed at which the film passes through the machine, a sprocket drum over which the film passes to the roll of film, a second sprocket drum over which the film passes to the machine, said sprocket drums being driven at a speed co-incident with the speed at which the film passes through the machine the respective rollers and discs being 100 so arranged that the main body of the roll is formed into a number of separate runs, and means for preventing the lateral displacement of the film upon the various rollers 105 comprising rollers arranged upon each side of the roll and engaging the edges of the film.

5. Winding mechanism for endless bands or films comprising film supporting rollers 110 engaging the inner convolution of the roll and driven thereby, other rollers engaging the inner convolution of the roll and driven thereby, discs associated with said second rollers and engaging the edge of the film 115 and driven at a speed co-incident with the speed at which the film passes through the machine, a sprocket drum over which the film passes to the roll of film, a second sprocket drum over which the film passes to the machine, said sprocket drums being driven at a speed co-incident with the speed at which the film passes through the machine the respective rollers and discs being 120 so arranged that the main body of the roll is 125 formed into a number of separate runs, and means for preventing the lateral displacement of the film upon the various rollers comprising rollers arranged upon each side of the roll and engaging the edges of the film.

formed into a number of separate runs means for preventing the lateral displacement of the film upon the various rollers comprising rollers arranged upon each side of the 5 roll and engaging the edges of the film and cradle rollers bearing upon the film on the sprocket drums.

6. Winding apparatus for endless bands or films comprising a plate, a spindle supported by said plate, a disc upon said spindle, a roll mounted upon but independently revoluble on said spindle said roll engaging the inner convolution of the roll of film and said disc engaging the edge of the said roll 10 of film, other spindles supported by said plate, rollers thereon carrying the roll of film and engaging and driven by the inner convolution thereof, a sprocket drum mounted on a spindle carried by the plate 15 over which the film passes from the interior of the roll to the machine, a second sprocket drum, a spindle therefor carried by the plate and over which the film passes to the roll and operating means for the disc and 20 sprocket arms whereby they are driven at a speed co-incident with the speed of the film passing through the machine.

7. Winding apparatus for endless bands or films comprising a plate, a plurality of 30 spindles supported by said plate, discs upon said spindles, a roll mounted upon but independently revoluble on said spindles said rolls engaging the inner convolution of the roll of the film and said discs engaging the 35 edge of the said roll of film, other spindles supported by said plate, rollers thereon carrying the roll of film and engaging and driven by the inner convolution thereof the various rollers being so arranged that the 40 roll of film is divided up into a number of independent runs, a sprocket drum mounted on a spindle carried by the plate over which the film passes from the interior of the roll to the machine, a second sprocket drum, a 45 spindle therefor carried by the plate and over which the film passes to the roll and operating means for the disc and sprocket arms whereby they are driven at a speed co-incident with the speed of the film passing 50 through the machine.

8. Winding apparatus for endless bands or films comprising a plate, a plurality of spindles supported by said plate, discs upon 55 said spindles, a roll mounted upon but independently revoluble on said spindles said rolls engaging the inner convolution of the roll of the film and said discs engaging the edge of the said roll of film, other spindles supported by said plate, rollers thereon carrying the roll of film and engaging and driven by the inner convolution thereof, the various rollers being so arranged that the 60 roll of film is divided up into a number of independent runs, a sprocket drum mounted on a spindle carried by the plate over which 65

the film passes from the interior of the roll to the machine, a second sprocket drum, a spindle therefor carried by the plate and over which the film passes to the roll and operating means for the disc and sprocket arms whereby they are driven at a speed co-incident with the speed of the film passing 70 through the machine, cradle rollers engaging the film on the sprocket rolls, comprising a pair of arms supporting the spindles of said rollers, other arms to which said first arms are connected in the centre of their length, a column supporting said second arms and secured to the plate, a spring acting upon 75 said second arms to cause said cradle rollers to press the film onto the sprocket roll.

9. Winding apparatus for endless bands or films comprising a plate, a plurality of spindles supported by said plate, discs upon 80 said spindles, a roll mounted upon but independently revoluble on said spindles said rolls engaging the inner convolutions of the roll of the film and said discs engaging the edge of the said roll of film, other spindles supported by said plate, rollers thereon carrying the roll of film and engaging and driven by the inner convolution thereof the 85 various rollers being so arranged that the roll of film is divided up into a number of independent runs, a sprocket drum mounted on a spindle carried by the plate over which the film passes from the interior of the roll to the machine, a second sprocket drum, a 90 spindle therefor carried by the plate and over which the film passes to the roll and operating means for the disc and sprocket arms whereby they are driven at a speed co-incident with the speed of the film passing 95 through the machine, cradle rollers engaging the film on the sprocket rolls, comprising a pair of arms supporting the spindles of said rollers other arms to which said first arms are connected in the centre of their length, a column supporting said second arms and secured to the plate, a spring acting upon 100 said second arms to cause said cradle rollers to press the film onto the sprocket roll, openings in said plate, spindles in said openings, rollers upon said spindles engaging the inner edge of the roll of film, 105 other spindles carrying other rollers engaging the outer edge of the roll of film, spindles carrying said rollers, columns attached to the plate carrying said spindles. 110

10. Winding apparatus for endless bands or films comprising a plate, a plurality of spindles supported by said plate, discs upon 115 said spindles, a roll mounted upon but independently revoluble on said spindles said rolls engaging the inner convolution of the roll of the film and said discs engaging the edge of the said roll of film, other spindles supported by said plate, rollers thereon carrying the roll of film and engaging and driven by the inner convolution thereof the 120 125

various rollers being so arranged that the roll of film is divided up into a number of independent runs, a sprocket drum mounted on a spindle carried by the plate over which the film passes from the interior of the roll to the machine, a second sprocket drum, a spindle therefor carried by the plate and over which the film passes to the roll, a pulley upon the spindle of the said first sprocket roll, pulleys upon the spindles of the discs a belt passing over said pulley on the first sprocket roll and drivingly engaging the pulleys on the spindles of the discs, a chain wheel on the spindle of the first sprocket roll, a chain wheel on the spindle of the second sprocket roll, a chain passing around said chain wheels, the various rolls being so arranged that the roll of film is divided up into a number of separate runs, cradle rollers engaging the film on the sprocket rolls, comprising a pair of arms supporting

the spindles of said rollers, other arms to which said first arms are connected in the centre of their length, a column supporting said second arms and secured to the plate, a spring acting upon said second arms to cause said cradle rollers to press the film onto the sprocket roll, openings in said plate, spindles in said openings, rollers upon said spindles engaging the inner edge of the roll of film, other spindles carrying other rollers engaging the outer edge of the roll of film, spindles carrying said rollers, columns attached to the plate carrying said spindles. 35

In testimony whereof I have hereunto set my hand in the presence of two witnesses.

RICHARD HAKING PARKINSON.
